ATTORNEY

UNITED STATES PATENT OFFICE.

FREDERICK HOLLENDER, OF NEW YORK, N. Y.

CORK-PROTECTOR.

SPECIFICATION forming part of Letters Patent No. 251,780, dated January 3, 1882.
Application filed October 26, 1881. (No model.)

To all whom it may concern:

Be it known that I, FREDERICK HOLLENDER, of the city, county, and State of New York, have invented certain new and useful Improvements in Cork-Protectors, of which the following is a specification.

This invention has reference to a covering or protecting plate for the corks of beer and other bottles, so that the heads of the corks are retained on a level with the bottle-mouth and the bulging up of the same at both sides of the wire is entirely prevented.

The invention consists of a cork-protecting plate which is provided with downwardly-projecting prongs which are pushed into the cork, and with one or more ribs or corrugations transversely to the connecting-line of the prongs.

In the accompanying drawings, Figure 1 represents a perspective view of a bottle with my improved cork-protector. Fig. 2 is a top view of the same as detached; and Fig. 3 is a vertical central section on line *x x*, Fig. 2.

Similar letters of reference indicate corresponding parts.

A in the drawings represents a circular plate of sheet metal of the size of the cork, which is provided with downwardly-bent prongs *a*, which are cut out of the plate, preferably at diametrically-opposite points, for the purpose of attaching the protecting-plate *A* to the cork by simply pressing the prongs down into the same. The fastening-wire by which the cork is retained is applied in the usual manner to the cork and passed diametrically over the protecting-plate *A*, preferably in line with the recesses left by the prongs, as shown in Fig. 1. At both sides of the prongs the protecting-plate *A* is provided with one or more raised ribs or corrugations, *b*, which are arranged transversely to the line connecting the prongs, and which serve for the purpose of imparting greater stiffness to the sides of the protecting-plate *A*, so that it resists the upward pressure of the cork at both sides of the wire. The ribs *b* also

serve to prevent the slipping off of the wire to either side of the plate. The cork-protecting plate keeps the cork down in the bottle-mouth, and is specially adapted for bottles containing fermented beverages which require to be exposed to the so-called "steaming process" before shipment, as by the plate the bulging up of the cork in steaming is effectively prevented and a neater and more finished appearance of the bottle obtained.

I am aware that metal cork-protectors having projecting prongs for holding the cap of the cork are well known; also cork-protectors having corrugations for holding the wires; and I do not claim these features, broadly. Neither one, however, is adapted for the purpose of protecting the corks while the bottles are exposed to steaming, as in this case a direct connection of the caps with the corks to prevent the shifting of the caps, as well as stiffening ribs or corrugations transversely to the fastening-wires, are required to resist the bulging up of the cork at both sides of the wires. These requirements are fully met by my improved cork-protector, which is specially designed for bottles containing fermented liquids which have to be exposed to the steaming process prior to shipment.

Having thus described my invention, I claim as new and desire to secure by Letters Patent—

A cork-protector for bottles containing fermented beverages to be exposed to steaming, consisting of a circular plate having downwardly-projecting prongs at diametrically-opposite points of the plate and one or more ribs or corrugations transversely to the line of the prongs at both sides thereof, substantially as specified.

In testimony that I claim the foregoing as my invention I have signed my name in presence of two subscribing witnesses.

FREDERICK HOLLENDER.
